PLASTIC MOULDING

Daniel Geltner, Fox Chapel, Pa., assignor to Parkins Products Corp., Pittsburgh, Pa., a corporation of Pennsylvania

Filed Nov. 13, 1967, Ser. No. 9,374

Term of patent 14 years

U.S. Cl. D13—6
Int. Cl. D25—03

FIGURE 1 is an isometric view of a plastic moulding embodying my new design;

FIGURE 2 is an enlarged sectional view of the moulding shown in FIGURE 1 and taken along reference line II—II thereof;

FIGURE 3 is an enlarged partial top isometric view of the moulding as shown in FIGURE 2;

FIGURE 4 is an enlarged partial bottom isometric view of the moulding as shown in FIGURE 2;

FIGURE 5 is a partial top isometric view of another form of moulding embodying my new design; and

FIGURE 6 is a partial bottom isometric view similar

to FIGURE 4 of still another form of moulding embodying my new design.

I claim:

The ornamental design for plastic moulding, substantially as shown.
